DESIGN FOR A HANDBAG OR THE LIKE

William F. Bowen, North Attleboro, Mass., assignor to Evans Case Company, a corporation of Massachusetts

Application October 5, 1936, Serial No. 65,175

Term of patent 3½ years

To all whom it may concern:

Be it known that I, William F. Bowen, a citizen of the United States, residing at North Attleboro, county of Bristol and State of Massachusetts, have invented a new, original, and ornamental Design for Hand Bags or the Like, of which the following is a specification, reference being had to the accompanying drawing forming a part thereof.

In the accompanying drawing Fig. 1 is a perspective view of a hand bag showing my new design in open position. Fig. 2 is a fragmentary perspective view thereof in closed position the bottom portion being omitted for convenience of illustration.

I claim:

The ornamental design for a hand bag or the like as shown, and described.

WILLIAM F. BOWEN.
